UNITED STATES PATENT OFFICE

JOHN R. GRUETTER, OF CLEVELAND, OHIO, ASSIGNOR, BY MESNE ASSIGNMENTS, TO THE CLEVELAND TRUST COMPANY, OF CLEVELAND, OHIO, A CORPORATION OF OHIO

BOTTLE-CLEANING APPARATUS

Application filed August 4, 1921. Serial No. 489,695.

This invention relates to bottle-cleaning apparatus, and has for its general object to provide an apparatus of this character which will not only enable the bottles to be cleaned efficiently but which, for its size, will enable a maximum number of bottles to be cleaned within a given time interval. A further object of the invention is to provide an apparatus of this character which, while possessing great efficiency and capacity, is relatively inexpensive of production. I accomplish the foregoing object and other and more limited objects to be explained hereinafter in and through an apparatus such as shown in the drawings forming part hereof, wherein Fig. 1 is a sectional front elevation; and Fig. 2 an end elevation of such apparatus; Fig. 3 a central sectional view through such apparatus; Fig. 4 a sectional view taken at right angles to that shown in Fig. 3; Fig. 5 a plan view of the apparatus, with parts broken away; and Fig. 6 a horizontal sectional view corresponding substantially to the line 6—6 of Fig. 1.

The apparatus illustrated herein comprises generally the following parts:

(a) A casing having a tank for the reception, heating and delivery of a caustic cleaning solution, with means within said casing for distributing the said solution to the bottles; also a preliminary cleaning and a final rinsing station within the said casing, with means for supplying liquid of the desired temperature thereto.

(b) A horizontally arranged rotatable carrier or turntable having bottle carrier elements secured to the periphery thereof and projecting radially therefrom.

(c) Means for applying intermittent rotary movement to the bottle carrier whereby the bottles thereon may be brought successively into operative relation to the cleaning jets.

(d) Means for automatically supplying liquid at proper temperature to the preliminary cleaning and final rinsing stations whereby the supply of heated water at these stations may be conserved.

The foregoing parts of the apparatus will now be described.

(e) The casing is relatively long and narrow

and has on the bottom thereof a tank 1 having a partition 2 thereabove, with a cover 3 above the said partition and forming therewith a hood for the reception of the cooperating part of the rotary bottle carrier and within which the various means for supplying cleaning liquid are located.

The side walls of the tank and casing are indicated at 4 and 5 and the bottom wall at 6. The tank 1 is supplied with liquid from time to time, as may be desired, by a pipe 7. A sufficient quantity of a caustic agent is dissolved in the water thus supplied to enable the bottles to be cleansed during the appropriate portion of their travel between the walls 2 and 3. The caustic liquid in the tank 1 is forced, by means of a pump 7^a having an inlet pipe 8 and a delivery pipe 9, into a jet box 10 having its cover provided with upwardly directed jet nozzles 11 (see Figs. 4 and 6), said nozzles being arranged in radial series, there being five such nozzles shown in each series to correspond to the bottle holders moving thereover, to be described hereinafter. In the apparatus shown in the drawings, the bottles are intended to be conducted above the nozzles in clockwise direction. Toward the exit end, the box 10 is provided with two series of jet orifices 12 in place of nozzles, the orifices being arranged

in groups of four in each series and adapted to discharge liquid upon the outsides of the bottles thereabove. Cooperating with the said orifices and nozzles as to the removal of labels and other sediment from the bottles, is a pan 13 arranged above the said jet box and supplied with liquid from the tank 1 and pump 7^a by a pipe 14 which is connected to the jet box (see Figs. 4 and 5).

The said pipe 14 has a horizontal extension 14^a at its upper end extending over said pan and discharging thereupon by means of the transverse distributing pipe 14^b. The pan is shown as supported by angle irons 15 connected thereto at 15^a which angle irons are supported by bolts 15^b passing through spacers 15^c and connected to T-bars 16 which in turn are supported from the casing by gusset plates 16^a and angle irons 16^b. The pan is provided with radial groups of sprink-

90

95

100

ling orifices 17, these radial groups corresponding in position and arrangement with the nozzles 11, four such orifices being shown for each group. The jet box 10 and the pan 13 are each in the form of a segment of an annulus, in order to cooperate with an annular bottle carrier which projects from the periphery of a turn table concentric with the inner and outer peripheries of said box and pan.

10 The liquid which is supplied to the bottles between the jet box 10 and the pan 13 is discharged into a label remover similar to that shown in the application of Charles H. Loew, Serial No. 426,630, filed November 17, 1920, 15 said label remover comprising a downwardly inclined tray 18 having its bottom perforated and into which the liquid, containing the labels and other sediment, is discharged from the partition or floor 2. From this tray, 20 the liquid which is strained through the openings therein passes through openings in a strainer 19, surrounding all but the inner side of the said tray, and down the inclined bottom of a box 20 back into the tank 1, where 25 it can be again taken up by the inlet pipe 8, and delivered by the pump 7^a and delivery pipe 9 to the box 10 and pan 13. For the purpose of maintaining the caustic solution 30 at the desired temperature, a radiator 21 is placed within the tank and is supplied with steam from any convenient source.

At the inlet end of the casing, between the partition 2 and cover 3, there is located a 35 single series of preliminary soaking and pre-heating jets, indicated at 22; while at the outlet or delivery end of the casing and preferably therewithin there is located a double series 23 of final cooling and rinsing jets, the 40 jets in both cases being similar to the jet nozzles 11 in the jet box 10, and adapted to discharge upwardly into and against the bottles on the carrier.

Cooperating with the jets 23 is a pan 24 having sprinkling heads 25 adapted to deliver the final cooling and rinsing liquid upon the exteriors of the bottles treated by the jets 23 therebeneath. The sprinkling heads are shown in Fig. 1, each head having 50 a plurality of jet openings adapted to discharge downwardly upon the bottles.

Water for the jet nozzles 22 and 23 and for the sprinkling heads 25 is preferably supplied from the local water system. 26 denotes the water supply pipe leading to the coil 27 within the tank (see Figs. 2 and 4); and from the said coil the heated water is delivered through the pipes 28, and 29 and valve 29^a to the upper jet box 24. The temperature 60 of the water thus supplied may be varied as desired by means of the connection 30 extending from the cold water pipe 26 to the pipe 29 and having the valve 30^a therein. By suitably manipulating the valves 29^a and 65 30^a, the temperature of the water which is

finally showered upon the bottles may be varied as desired. The pipe 28 is extended beyond its point of connection with the pipe 29 and is there provided with a valve 31 which is adapted to be opened automatically (under conditions to be pointed out hereinafter) thereby to supply water at the desired temperature to the final rinsing nozzles 23. Through the valve 31 and pipe connections 32^b and 32^a, warmed or heated water 70 is delivered to the preliminary soaking and preheating jets 22 (see Figs. 1, 2 and 6). The manner in which the flow of liquid through the jets 22 and 23 is automatically controlled will be more fully pointed out hereinafter. By reference to Fig 2 it will be seen that the valve 31 is below the pipes 32 and 32^b which lead respectively to the nozzles 23 and 22. The valve 31 is automatically actuated from the turntable shaft to control the flow of liquid to the jets 22 and 23 in the manner to be hereinafter more fully described. The inlet opening and the outlet opening from the casing are provided with vertical flaps, 33, 34 respectively, said flaps 80 being adapted to be swung aside by each radial series of bottles entering and leaving the casing and to drop thereafter by gravity into a position to approximately close such openings.

Concentric with the peripheries of the jet box 10 is a post 35 mounted in the horizontal arms 37 of a bracket 36. Sleeved upon the upper end of this post and rotatably supported upon the upper bracket arm 37 is a 100 horizontal turntable 38, having at its periphery a vertical flange 39 provided with radial lugs 40. Bolted onto the said lugs are the annular segments 41 of the bottle carrier. Each segment, as shown herein, comprises a 105 grid made up of three radial bars 42 connected by five cross bars 43. The intersection of each cross bar with each radial bar is provided with an open seat 44 for the neck and breast of a bottle. Each seat 44 is generally circular in plan and is provided with inwardly projecting beveled radial projections 45 which are adapted to receive the breast of the bottle, with the neck projecting downwardly through the circular opening. The bottle holders are so arranged and spaced as to register with the jet nozzles 22, 11 and 23 as the bottle carrier is advanced intermittently about the post 35 as an axis. For the purpose of lightening the construction, the 110 turntable 38 is provided with openings 38^a therethrough and is strengthened by radial ribs 38^b between such openings.

For the purpose of imparting the intermittent rotary motion to the turntable and to the bottle carrier thereon, the following construction is provided: 46 denotes a shaft 125 arranged parallel with the post 35 and driven in any convenient manner, and preferably in connection with the pump. In the drawings, 130

the shaft 46 is shown as driven as follows:—
47 denotes an electric motor the shaft 48
whereof is used as the shaft for the pump 7a.
The shaft 48 is extended and provided with
6 a pulley 49 by means of which a belt 50, a
pulley 51, and a shaft 52 are driven. The
latter shaft is provided with a worm 53 meshing
with a worm gear 54 on the shaft 46, the
driving connections described operating the
10 shaft 46 at a speed very greatly reduced as
compared with the shaft 48.

The shaft 46 is mounted within a housing
55 having at its upper end a bearing for the
upper end of said shaft. The extreme upper
15 end of the shaft projects above said housing
and is there provided with a cam 56. As
shown herein, this cam is approximately 90°
in angular extent and is adapted to engage a
roller 57 intermediate the ends of an arm 58
20 which is sleeved at one end upon the post 35.
The opposite end of the arm 58 has pivotally
connected thereto, at 59, a pawl 60 which, by
means of a spring 61, is pressed into engagement
25 with the teeth 62 of an annular ratchet
formed within the flange 39 of the turntable.
A spring 63 holds the roller 57 in engagement
with the cam 56. It will be evident that, by
rotation of the shaft 46 and the cam 56, an inter-
30 mittent rotary movement is imparted to
the turntable 38 and to the annular bottle car-
rier secured thereto. The ratchet teeth 62 will
be so spaced and the throw of the pawl will
be such that the turntable will be advanced
35 the angular distance between two adjacent ra-
dial rows of jet nozzles or orifices for each ro-
tation of the shaft 46.

Reference has been made hereinbefore to
the automatic operation of the valve 31. This
automatic operation is secured by a second
40 cam 64 carried by the shaft 46 below the cam
56, which cam 64 is adapted, during each ro-
tation of said shaft, to engage one end of an arm
65 pivoted intermediate of its ends to a
45 bracket 66, as indicated at 67, the opposite
end of said arm being connected by a link 68
with an operating arm 69 rigid with the stem
70 of the rotary valve 31. A spring 71, con-
nected to the arm 68 and to a suitable part of
50 the apparatus, serves to hold the said arm in
55 operative relation to the cam 64. The parts
are so arranged that the valve 31 will be closed
except when the cam 64 is operating the arm
65, and the parts are so timed that the maxi-
55 mum opening of the valve will not occur un-
til the bottle mouths are in register with the
various radial series of jet orifices and jet
nozzles. This is due to the shaping of the
cam 64 and its arrangement with reference to
60 the cam 56. It will be noted that the peak
65 of the cam 64 is of very short extent and that
this peak is located between the ends of the
peak of the cam 56 (see Fig. 5). With this ar-
rangement, with the cams rotating in a counter
clock-wise direction, the cam 56 will first
65 operate to move the arm 58 to the left, thereby

rotating the turntable one step. The arm 58
will be held in this position until the roller
rides off the right hand end of the curved
peak of the cam 56, when the spring 63 will
move the arm 58 to the right so that the pawl
70 60 may engage the next tooth of the ratchet
62. During the time that the arm 58 is thus
held in its left-hand position, by the peak of
the cam 56, the peak of the cam 64 will have
engaged the arm 57, thereby quickly open-
75 ing the valve 31 and opening it only at a time
when the turntable is at rest. As soon as the
arm 57 rides off the peak of the cam 64, the
valve 31 will be closed, and this closing will
occur before the arm 58 can be moved to the
80 right, as a necessary step before the next move-
ment of the turntable. This results in supply-
ing the pre-heating liquid and the final rins-
ing liquid to the bottles during a portion only
85 of the period in which the bottle carrier is at
rest, thereby conserving the supply of liquid
to the preliminary and final stations and es-
pecially the supply of water heated by the
liquid within the tank.

The operation of the apparatus as thus
described will be easily understood from the
foregoing description. The bottles are re-
moved from and applied to the rotatable car-
rier between the delivery flaps 34 and the in-
let flaps 33. Drain pans are provided for the
90 part of the carrier outside of the casing, as
indicated at 72 and 73. The radial series of
bottles will be carried successively into regis-
ter with the radial series of jet nozzles 22,
where they will be preliminarily soaked and
95 warmed. The liquid from this operation will
be delivered to the pan 74 which, in common
with the pans 72 and 73, may discharge their
contents to the sewer or other waste place.
Between the jets 22 and the outlet jets 23, the
100 bottles are subjected to the action of the solu-
tion pumped from the tank 1. With the parts
shown herein, the bottles will be given five
consecutive internal cleansing actions before
they reach the first radial series of external
105 cleansing jets 12, where they will be subject-
ed to upwardly directed streams of liquid
flowing along the outer sides thereof. Fol-
lowing this action, the bottles will be given
another internal cleansing action, and two
110 more internal cleansing actions. While pass-
ing above the box 10, the sides and the up-
turned bottoms of the bottles will be sprinkled
with solution discharged from the openings
115 17 in the pan thereabove. The liquid sup-
plied to the bottles at this stage of the opera-
tion will be delivered into the combined
strainer and label remover comprising the
parts 18—20 and will be returned to the tank
120 1 for re-use.

The bottles next pass to the final rinsing
and cooling station comprising the nozzles 23
and the jets 25 and, after passing through the
flaps 34 of the delivery opening, can be re-
moved by the operator.

It will now be clear that I have provided a bottle cleaning apparatus which will accomplish the objects of the invention as hereinbefore stated.

Having thus described my invention, what I claim is:

1. In an apparatus for cleaning bottles, the combination of a tank for cleansing solution and a casing above said tank, the said casing being provided with a lower spraying device and an upper spraying device for supplying liquid to bottles therebetween, means for forcing the solution from said tank to the said devices, a turntable having bottle supports at its peripheral portion adapted to pass between the spraying devices, and means for driving said turntable intermittently thereby to bring the bottle supports into register with the said spraying devices, additional spraying devices arranged within said casing and means for supplying a cleaning fluid thereto, means operated by said turntable driving means for limiting the supply of fluid through said last mentioned spraying devices for predetermined periods.

2. In an apparatus for cleaning bottles, the combination of a tank for cleansing solution and a casing above said tank, the said casing being provided with a lower jet box and with a liquid distributing device above and spaced from the jet box, means for forcing the solution from said tank to the said jet box and to the said device, a turntable having bottle supports at its peripheral portion, and means for driving said turntable intermittently thereby to bring the bottles on the supports into register with the jets and the distributing device, additional spraying devices for supplying a cleaning fluid to said bottles and means for supplying cleaning fluid thereto, and means operatively connected with the turntable driving means for limiting the supply of fluid through said last mentioned spraying devices for predetermined periods.

3. In an apparatus for cleaning bottles, the combination of a casing having in its lower portion a tank for cleansing solution and having therein and above said tank a jet box provided with radial series of jet openings and with a sprinkling device above and spaced from the jet box, a turntable having radial series of bottle supports adapted to be carried successively in operative relation to the series of jet openings, means for driving said turntable intermittently to bring the bottles thereon into register with the series of jet openings successively, and means for forcing solution from the said tank to the said jet box and to the said sprinkling device, and additional spraying devices carried by said casing and means for supplying a cleaning fluid thereto, means operatively connected with the turntable driving means for limiting the supply of fluid through said last mentioned spraying devices for predetermined periods.

4. In an apparatus for cleaning bottles, the combination of a casing having a tank therein, series of jets forming an annular segment within the said casing, a turntable having its axis located outside of said casing and provided with a peripheral annular bottle carrier comprising radial series of seats, means for supplying liquid from the said tank to the said jets, and means for imparting intermittent rotary motion to the said turntable whereby the bottle carrying seats will be moved into and out of the upper portion of the casing and into register successively with the series of jet openings in said casing, additional spraying devices for supplying a cleaning fluid to bottles supported on said bottle carriers and means for supplying a cleaning fluid thereto, means operatively connected with said turntable driving means for cutting off the supply of fluid through said last mentioned spraying devices for predetermined periods.

5. In a bottle cleansing apparatus, the combination of a liquid containing tank and means for heating the liquid therein, a bottle spray station having a plurality of spraying devices, and means for supplying heated liquid from said tank to said devices, a coil in said tank, a second bottle spraying station having spraying devices connected with and supplied from said coil, a horizontally disposed rotatable bottle carrier, means for moving the said carrier intermittently, thereby to bring the bottles thereon successively in operative relation to the spraying devices at both of said stations, and means operated in conjunction with the movements of said carrier for admitting liquid to the spraying devices at the second station only when the bottles are in register with the said devices.

6. In a bottle cleaning apparatus, the combination of a tank having means for heating liquid therein, a plurality of bottle cleaning devices and means for supplying liquid from said tank thereto, a coil in said tank, a second series of bottle cleaning devices and means for supplying liquid from said coil thereto, a bottle carrier, means for moving the same intermittently thereby to bring the bottles thereon successively in operative relation to both sets of cleaning devices, and means operative in conjunction with the driving of the bottle carrier for limiting the supply of liquid from the coil to the second series of cleaning devices.

7. In a bottle cleaning apparatus, the combination of a radial series of bottle cleaning devices and means for supplying liquid thereto, a turntable having an annular ratchet and provided with radial series of bottle supports adapted to be brought into register with the said cleaning devices, a drive shaft, an arm pivoted coaxially with the said turntable and having a pawl adapted to engage the said

ratchet, and a cam on said drive shaft adapted to engage said arm.

8. In a bottle cleaning apparatus, the combination of a plurality of bottle spraying devices, a turntable having bottle supports adapted to register with said spraying devices, a pipe for supplying liquid to said spraying devices, a valve in said pipe, an axial support for said turntable and an annular ratchet carried by the latter, a pawl for operating said ratchet, a drive shaft having a cam thereon for operating said pawl, a second cam on said drive shaft, and connections between said second cam and said valve for opening the latter when the bottles on the carrier are brought into register with the said spraying devices.

9. A bottle cleaning apparatus comprising a series of bottle spraying devices and means for supplying liquid thereto, a turntable and means for imparting intermittent rotary movement thereto, said turntable being provided with marginal lugs, and bottle-carrying elements secured to said lugs and forming an annular bottle carrier about the periphery of the said turntable, and means operated by the movement of the turntable for controlling the supply of liquid to said spraying devices.

10. In an apparatus for cleaning bottles, the combination of a plurality of bottle spraying devices and means for supplying a liquid thereto, a turntable rotatably supported adjacent said spraying devices and having a plurality of bottle supports thereon, means for imparting an intermittent rotary movement to said turntable whereby to move said bottle supports into register with said spraying devices successively, and means actuated by the driving means for said bottle supports for cutting off the delivery of fluid through said spraying devices when said bottle supports are out of register therewith and additional means for delivering a liquid to the outside of the bottles during a part of their movement.

45 11. In an apparatus of the class described, the combination of a casing having a plurality of radially disposed rows of bottle cleaning spray nozzles therein and means for supplying a liquid thereto, a turntable rotatably supported and having a part projecting into said casing, a plurality of radially disposed bottle supports carried by said turntable, means for imparting an intermittent rotary movement to said turntable whereby to move said bottle supports into register with said spray nozzles in regular sequence, said last mentioned means including a driven shaft, means operatively connected with said shaft for cutting off the supply of liquid to said spray nozzles when said bottle supports are out of register therewith, a second series of radially disposed cleaning spray nozzles arranged within said casing and means for supplying a different cleaning fluid thereto from an independent source of supply and additional

means for delivering a liquid to the outside of bottles arranged on said bottle supports.

12. The combination with a liquid containing tank and means for heating the liquid therein, of a casing above said tank, there being a radial series of bottle cleaning jets disposed within said casing and arranged to discharge into the mouths of bottles thereabove, said casing having a radial series of orifices therein arranged to discharge upon the outside of bottles brought thereabove, means located above the said jets for showering liquid upon the sides and bottoms of bottles above said jets, a second series of jets arranged to discharge into the mouths of bottles thereabove, a sprinkling device arranged above the last mentioned jets, means for delivering a preliminary rinsing liquid to the first series of jets and means for delivering a rinsing liquid to the last series of jets and to said sprinkling devices, a turntable having a radial series of bottle supports, means for driving said turntable intermittently to bring the bottles on said supports successively into operative relation to the various jets and sprinkling devices within said casing, and means operated by the movement of said turntable for controlling the flow of liquid to said first mentioned jets.

13. The combination with a liquid containing tank and means for heating a cleaning liquid therein, of a casing above said tank, said casing having a radial series of orifices therein, a showering device disposed above said orifices, means for supplying a heated liquid from said tank to the said orifices and to the said showering device, preliminary bottle rinsing means arranged within said casing, means for delivering liquid to said preliminary rinsing means, final rinsing means arranged near the delivery end of said casing, means for supplying a cooling liquid to said final rinsing means, a turntable having a radial series of bottle supports thereon, and means for driving said turntable intermittently thereby to bring the bottle supports successively into operative relation to the various liquid supply means within the casing.

14. The combination, with a liquid containing tank and means for heating the liquid therein, of a casing disposed above said tank, said casing having a radial series of bottle cleaning orifices therein, a radial series of jets within said casing and arranged to discharge water into and upon the sides of bottles brought thereabove, means located above the said jets for discharging water upon the bottoms and sides of bottles brought above said jets, there being within said casing a second radial series of orifices arranged to discharge into the mouths of bottles brought thereabove, a turntable having a radial series of bottle supports, means for driving said turntable intermittently to bring bottles on said supports successively into operative relation

to the various liquid supplying devices within said casing, means for supplying heated liquid from said tank to said jets and to the external cleaning means thereabove, and means for supplying the preliminary and final rinsing water to the first and last radial series of orifices in said casing respectively.

15. In a bottle cleaning apparatus, the combination with a liquid containing tank, of a casing having a series of orifices therein, a spraying device disposed above said orifices, means for supplying a liquid from said tank to the said orifices and to the said spraying devices, preliminary bottle rinsing means carried by said casing means for delivering liquid to said preliminary rinsing means, final rinsing means arranged near the delivery end of said casing, means for supplying a cooling liquid to said final rinsing means, a turntable having a series of bottle supports thereon and means for driving said turntable intermittently whereby to bring the bottle supports successively into operative relation to the various liquid supply means.

20 15. In testimony whereof, I hereunto affix my
25 signature.

JOHN R. GRUETTER.
